UNITED STATES PATENT OFFICE

2,401,350

RECORDING APPARATUS

Reinhard K. Hellmann, Meriden, Conn., assignor to Connecticut Telephone & Electric Division, Great American Industries, Incorporated, Meriden, Conn., a corporation of Delaware

Application April 17, 1944, Serial No. 531,374

18 Claims. (Cl. 234—1.5)

1

My invention relates to recording apparatus for measuring, signal-transmitting, facsimile transmitting or the like purposes and is related to the invention disclosed and claimed in the copending patent application of George Keinath and Reinhard K. Hellmann for Recorders, Serial No. 531,375, filed April 17, 1944.

The known drum type recorders have a stylus which produces a record along the peripheral surface of a cylinder or drum member, usually by writing point or line marks on a recording sheet fastened around the cylindric member. The cylindric member and recording surface in known devices of this kind revolves about its axis while the stylus moves in parallel thereto. The drum rotation and stylus travel are representative of the two coordinates, respectively, of the recorded diagram and are controlled in accordance with two measuring quantities, one of which is frequently time.

Compared with the so-called strip-chart recorders, i. e., recording apparatus in which a diagram is plotted along a progressively advancing, non-rotating strip, the above-mentioned drum-type recorders have the advantage of permitting higher recording speeds and are often also distinguished by a relatively simple construction. As heretofore customary, however, these recorders have the disadvantage that the diagram cannot readily be observed while it is being recorded. This is particularly true for apparatus of high operating speed as well as for multiple recorders. The application of stroboscopic observation means adds an intricacy and is not always satisfactory. Hence, it is usually necessary to arrest the recorder drum in order to permit observing a partially recorded diagram. As a result, the recording operation must be interrupted during any such observation.

It is an object of my invention to devise a recording apparatus that combines the advantages of the above-mentioned known type recorders, i. e., permits a higher operating speed than the known strip chart recorders while avoiding the difficulty of observing the growing record heretofore peculiar to drum type recorders.

It is also an object of my invention to provide a drum-type recording apparatus which affords visibility of the record any time during a recording operation without requiring an interruption of the operation.

Another object of my invention, allied to the one just mentioned is to devise a drum-type recorder in which the record or partial record remains stationary and hence is readily visible and

observable during the entire recording procedure.

A further object is to provide a drum-type recorder in accordance with the aforementioned objects which is especially suitable for X-Y recording, i. e., which can readily be applied in cases where neither component control quantity or diagram coordinate is necessarily proportional to time.

A still further object of my invention is the provision of a recording apparatus for producing a stationary record, especially at high speed operation, that is suitable for inkless recording as obtained, for instance, with electrolytic recording sheets known under the trade name Teledeltos paper. However, it is also an aim of my invention to afford the above-mentioned advantages with recorders of the continuously writing type such as ink and pen recorders.

It is also an object of the invention to devise a recording apparatus in which a device for controlling the recording operation is combined with the recorder structure and operated by drive or transmission means for producing one or both components of the relative drum and stylus travel, so that the mechanically driven parts necessary for operating the apparatus form a single structural unit.

Having these objects in mind, I provide, according to one feature of my invention, a recording apparatus with stylus means that are arranged relative to the drum or other cylindrical sheet-accommodating member so as to be capable of unidirectional continuous rotations about the axis of the said drum or member while performing an axial translating motion relative thereto. According to another feature, related to the one just mentioned, the drum or other cylindric member of the recorder is stationary or non-rotating during the normal recording operation so that the diagram or record remains observable while it is being produced by the moving stylus means. Another feature of the invention consists in providing a cylindric sheet-accommodating recorder member or drum that is stationary or non-rotating while the stylus means, rotating about the drum, produces the record but can be revolved by the observer in order to place the record into a convenient position.

In another aspect of the invention, I provide an annular stylus carrier which surrounds a cylindric recorder member and is capable of rotation about the axis of the recording sheet accommodated on the peripheral surface of the member, cooperative drive means being provided to effect

a relative axial motion between sheet and stylus means during the rotation of the latter.

In a further aspect of the invention, the rotating stylus means of a recorder designed in accordance with one or several of the features aforementioned, or the drive for rotating the stylus means about the axis of the cylindric recording surface, is connected by gears, shafts or the like transmissions with the movable control member of a mechanism serving to control the recording operation so that the control device forms part of the recording apparatus and operates in synchronism with and in a given speed ratio to the rotations of the stylus means.

The above-mentioned as well as more specific objects and features of my invention will be apparent from the following description of the embodiments shown in the drawings, in which:

Figure 1 shows a sectional lateral view of a recording apparatus having a vertical drum axis;

Fig. 2 is a sectional top view of the same apparatus, the section being taken along a cut denoted in Fig. 1 by a dot-and-dash line marked II--II;

Fig. 3 shows a sectional bottom view of the apparatus of Fig. 1;

Fig. 4 is an explanatory diagram relating to the same apparatus and represents a schematic illustration of some of its mechanisms in connection with electric circuit means suitable for its operation;

Fig. 5 shows a modified detail of the apparatus according to Fig. 1;

Fig. 6 represents a partly sectional side view of another recording apparatus having a horizontal drum axis;

Fig. 7 is a bottom view of the recorder drum appertaining to the apparatus according to Fig. 6 and shown separate from the other parts of the recorder;

Fig. 8 is a partial and sectional view of a further embodiment of a drum-type recorder according to the invention;

Fig. 9 is an explanatory diagram illustrating an ink recorder on the principles of my invention by showing schematically some of its mechanical parts in connection with the appertaining electric control means in a manner comparable to that of Fig. 4; and

Figs. 10, 11 and 12, respectively, represent diagrammatically three further embodiments of my invention each involving a recorder mechanism similar or related to that shown in Figs. 1 through 5.

Referring at first to the recording apparatus according to Figs. 1, 2 and 3, letter B denotes a base structure which comprises a housing 11 with a closure plate 12 and forms a horizontal base plate 13. An insulator 14 screwed to plate 13 carries a dowel pin 15 which engages the bottom plate 16 of the recorder drum D. The top plate 17 of drum D, which like plate 16 is rigidly secured to the metallic drum cylinder 18, carries a stud 19 with a knob 20 of insulating material firmly mounted thereon. The stud 19 is journalled in an insulating bearing plate 21. An annular end plate 22, rigidly secured to the base structure B, has several dowels, like the one denoted by 23 in Fig. 1, which engage the bearing plate 21 for maintaining it in centered position. The drum D and its bearing plate 21 can be removed, for the purpose of fastening recording paper to the drum cylinder 18, by pulling the entire drum assembly upwardly through the center opening 24 of the end plate 22.

The stylus assembly S of the recorder com-

prises an electrode pin 25 attached to an angular holder 26 which is pivoted at 27 to a bracket 28. This bracket is firmly mounted on a flange portion 29 of an annular carrier member M whose lower portion carries a gear 30. The flange portion 29 is engaged by three equally spaced rollers 31, 32 and 33 (see Fig. 2), revolvably mounted on an annular support 34. The two annular parts M and 34 surround the drum D coaxially but, while the member M with the stylus assembly is rotatable about the drum, the support 34 is prevented from rotary motion by engagement with two threaded shafts or feed screws 35 and 36 (Figs. 1, 2 and 3) serving to advance the support 34 along the drum, thereby also moving member M and stylus assembly S in parallel motion along the peripheral drum surface. The engagement between the support 34 and each feed screw is obtained by a releasable nut device such as the one shown in Figs. 1 and 2 at feed screw 35. The device has a sleeve 37 in sliding engagement with the feed screw 35. A lever 38, pivoted at 39 to a ring shaped cover member 40, has a threaded nut portion 41 extending through a slot of sleeve 37 and is biased by a spring 42 toward engagement of nut portion 41 with feed screw 35. In this manner, the support 34 is normally in operative engagement with the feed screws. A projection 43 of lever 38 extends toward an inwardly bent tongue 44 formed by a cut-out portion of member 40 but is normally out of engagement therewith (Figs. 1 and 2). Member 40 is rotatable to a limited extent relative to support 34 and, if rotated by hand in the proper direction, will cause its tongue 44 to engage the cam surface of projection 43 and thus force lever 38 toward the drum axis against the bias of its spring 42 thereby releasing the nut portion 41 from the feed shaft. The whole assembly carried by support 34 can then be slid up and down along the drum.

The stylus pin 25 is normally held against the surface of drum D by means of a spring 45. It is desirable to lift the stylus pin when manually displacing the assembly. To this end, a pin 46 extends loosely through the bracket 28 and carrier M so that its lower end lies closely above the skirt surface of cover member 40. Member 40 and support 34 are in threaded or cam engagement with each other at 47 so that when the cover member 40 is rotated in order to release the carrier from the feed screws 35 and 36, the cover member is also raised and lifts pin 46. As a result, holder 26 rotates counter-clockwise and lifts stylus 25 from the drum.

A modified structure for lifting the stylus is shown in Fig. 5. In this alternative construction, the stylus 25 is mounted on a lever 47 whose lower end carries a weight 48. When the annular carrier M is non-rotating, the pendulum formed by the stylus, lever and weight is so balanced that the stylus point is lifted from the drum. During rotation of the carrier M, the weight 48 swings outwardly, due to centrifugal force, and presses the stylus 25 against the drum.

Reverting now to Figs. 1 to 3, numeral 49 denotes a shaft which extends through the base plate 13 (Figs. 2 and 3) toward and through the end plate 22 (Fig. 1) and is square or keyed along the length of drum D. Shaft 49 passes through a gear 50 (Fig. 2) with a correspondingly non-circular opening, so that the gear cannot rotate but is free to slide relatively to shaft 49. Gear 50 has two bearings in the annular support 34 and in a strip 51, respectively, the strip being attached to support 34 with enough clearance to accommo-

date the gear. Gear 58 meshes with the gear portion 38 of carrier member M.

It will be understood from the foregoing that, when shaft 49 is caused to revolve, carrier member M and stylus assembly S rotate about the drum D and at the same time can be displaced axially along the drum by revolving the feed screws 35 and 36.

The transmission and drive means for actuating the shaft and screws are mounted on or arranged within the housing 11 of base structure B as is apparent from Figs. 1 and 3. These means, as exemplified in the embodiment here described, refer to a recorder for diagrams in which the coordinate parallel to the drum axis represents time or is proportional to time. Shaft 49 for rotating the stylus assembly carries at its end a bevel gear 52 meshing with a bevel gear 53 on the shaft 54 of an electric motor 55 which is mounted on base structure B. When the motor runs at constant speed, the stylus assembly is rotated about drum D at a speed determined by the transmission ratio of gears 53 to 52, and 50 to 38. With a motor of 1800 R. P. M. rated speed, for instance, a stylus rotation of, say, 600 R. P. M. can be obtained for high-speed recording operation.

A pinion 56, also mounted on shaft 49, drives an idler gear 57, which in turn engages with gears 58 and 59 fastened to the feed screws 35 and 36 respectively. Consequently the two feed shafts will revolve at a fixed speed relative to that of the stylus rotation and move the stylus slowly along the drum, for instance, from the top to the bottom of the drum, the resultant stylus motion being along a helical path of many turns so as to scan the entire area of the recording surface during each complete recording period. At the end of its downward travel, the carrier may actuate a limit switch (not shown) which stops the drive or disengages the carrier from the feed screws.

During the just-mentioned scanning motion, the stylus 25 runs idle, that is, it produces no recording marks on the sheet placed on the drum D except at one or several points of each individual stylus rotation at which an electric current is passed between stylus and drum through the electro-responsive recording paper mounted on the drum. The electric means for controlling this marking operation comprise a variable circuit member, preferably an impedance or potentiometric device, which has a movable adjusting or control member actuated in a fixed speed relation to one component of the stylus motion relative to the drum. In the embodiment of Figs. 1 to 3, the electric device for controlling the stylus operation consists of a resistance potentiometer P (Fig. 1) which has an insulating base 60 mounted on three studs 61, 62 and 63 (Figs. 1 and 3) fastened to the base plate 13. The base 60 carries and encloses a resistor 68 (in Fig. 4) and has a bottom plate 64 (Fig. 1) provided with a number of contacts, such as those denoted by 65, which are circularly arranged for engagement by a resilient slide contact 66. The carrier or hub 81 of contact 66 is mounted on the shaft 67 of the idler gear 57. It is desirable to make the ratio of gears 56 and 57 (Fig. 3) the same as that of gears 50 and 38 (Fig. 2) so that the angular speed of the slider 66 (Fig. 1) is the same as that of the stylus 25. If the apparatus is intended for use as a multiple recorder, the rotary speed of the slider must be an integral multiple of that of the stylus rotation in order to produce several separate recordings in peripherally successive areas of the recording sheet. This can be obtained, for in-

stance, by driving the slider from shaft 49 (Fig. 3), provided the ratio of gears 56 and 57 is an integral number or fraction.

The electric control and measuring circuit for operating the recording apparatus includes as a rule, besides the above-mentioned impedance or potentiometric device, some measuring gauge or other circuit means responsive to the quantity whose variations are to be recorded and has also a relay associated with the gauge or circuit means as well as with the impedance or potentiometric device. One of the many control circuits applicable with the above-described recording apparatus is shown diagrammatically in Fig. 4. Only those mechanical parts of the recorder are represented in this schematic showing that have to be referred to for explaining the operation, and these parts are denoted by the same reference characters as are used in Figs. 1 to 3 for corresponding items. The feed screws and other transmission and drive means for moving the stylus assembly S axially along the drum D are not shown in Fig. 4 because it will be clear from the foregoing that this longitudinal motion is derived from the idler gear 57 and that the angular member M, while rotated by gear 50 through shaft 49 and the bevel gears 52, 53 driven by motor 55, advances simultaneously from the left to the right of drum D as shown in Fig. 4. During each rotation of the stylus, the slider 66 of potentiometer P passes once through its complete cycle relative to the appertaining resistor 68 here shown simply as a slide wire.

The drive and transmission mechanisms are at ground potential. The insulated drum D is connected to a control circuit C (Fig. 4) through the dowel pin 16 and a terminal lug 69 (Fig. 1). The stylus assembly S is likewise connected to circuit C so that the recording sheet on drum D lies in a discharge gap between the drum surface and the stylus point. The circuit C includes a capacitor 70, a direct current source or battery 71 series-connected with a resistor 72, and a relay R whose movable contact 73 is normally biased by a spring 74 toward a stationary contact 75 and switches over to another stationary contact 76 when the relay coil 77 is energized to an extent sufficient for overcoming the spring bias. The capacitor 70 is normally connected to the current source 71 and hence in charged condition. When contact 73 switches over to contact 76, the capacitor 70 is disconnected from source 71 and discharges itself through the stylus and drum, this discharge being of very short duration so that a dot mark is produced on the recording sheet.

The relay coil 77 derives its energization from a measuring circuit under control by the potentiometer P. A measuring gauge G, here represented by a thermocouple although any other type of gauge, impulse or signal transmitter may be used, is connected across the potentiometer resistor 68, for instance, through an amplifier A. The voltage drop along resistor 68, between its terminal points 78 and 79, varies in accordance with the variations of the quantity (temperature) measured by gauge G and is so rated, relative to the minimum (threshold) excitation required by coil 77 for actuating the relay contact 73, that the threshold voltage of the relay lies within the range of the expected potentiometric voltage variations. When the slider 66 begins its travel at terminal point 78, the voltage drop across relay coil 77 is zero so that the stylus, now also at the starting point of a rotation, is de-

energized. As the slider 66 travels along resistor 68 toward terminal point 79, it will reach a point where the voltage imposed on the relay coil passes through the threshold value. At this moment, the movable relay contact 73 is switched over so that a self-terminating short-lasting discharge is released and a recording point produced by the stylus. While the slider 66 continues its travel, contact 73 remains in engagement with contact 76 so that no further recording action occurs. At the end point 79 of the slider travel, the coil circuit of the relay is interrupted. While the slider 66 passes from point 79 to point 78, contact 73 returns to contact 75 thus charging capacitor 70 for the next operation.

The point along resistor 68 at which the threshold voltage of the relay is obtained depends on the voltage value imposed on the resistor at that moment and hence is indicative of the quantity to be measured. Since the angular position of the stylus relative to the drum is in a fixed relation to that of the slider 66 relative to resistor 68, the position of the recording mark produced by the stylus on the recording sheet is also indicative of the measured quantity. The recording procedure is repeated during each rotary cycle of stylus motion. Hence, a resultant curve 80 (Figs. 1 and 4) is recorded representing the variation of the measured quantity versus time.

It will be understood from the foregoing that the recorder drum is non-rotating during the recording operation. As a result the record, represented by curve 80, remains stationary and can be readily observed at all times even at high operating speeds, for instance 600 R. P. M. of stylus rotation. However, the drum can be adjusted to any desired angular position relative to the base structure of the recorder merely by turning the knob 20 (Fig. 1). This may be used for selecting the location of the recording sheet on which the diagram is to appear. The rotary adjustability of the drum is also of advantage in cases where the recorder is mounted so that only one side of the drum is conveniently visible to an observer. That is, by turning knob 20 any part of the diagram can be moved into a desired angular position, although when this is done during a recording operation, the continuity of the recorded diagram will be interrupted as long as the drum is out of its normal or starting position. Unless this is undesirable the recorder need not be stopped. A modification which avoids such diagram discontinuity will be described presently with reference to the horizontal drum type recorder shown in Figs. 6 and 7.

The apparatus according to Figs. 6 and 7 has a base structure B, a recording drum D, a stylus assembly S carried by an annular member M, and a resistance potentiometer P corresponding to the similarly denoted parts of the recorder previously described. The stylus assembly is rotated about the drum and advanced along the drum by means of transmission and drive mechanisms largely similar to those of the first-described embodiment. In order to indicate these similarities, and for permitting a briefer description of the parts thus concerned without loss in clarity, the same reference numerals are used in Fig. 6 for individual items functionally or structurally similar to those of Figs. 1 to 3, except that in Fig. 6 the prefix 1 has been added to these numbers of comparable items. For instance, cover member 140, feed screws 135, 136, and gears 152, 153, 158 and

159 in Fig. 6 correspond to the respective elements 40, 35, 36, 52, 53, 58 and 59 in Figs. 1 to 3.

When in operation, the motor shaft 154 (Fig. 6) drives a bevel gear 153 meshing with a bevel gear 152 which drives an idler gear 157 and, through gears 158 and 159, causes the feed screws 135 and 136, respectively, to advance the axially movable assembly, including members 140, M and the stylus assembly S, along the drum D, while the member M and stylus are rotated. The electric control of the recording operation may be carried out by circuit means of the type exemplified by Fig. 4.

The apparatus of Figs. 6 and 7, however, differs from the preceding embodiment as regards the following features.

The idler gear 157 is so arranged that its center coincides with the axis of drum D and is mounted, together with the motor-driven bevel gear 152 and the carrier 151 of the slider 166, on a sleeve 82 which runs freely on the drum shaft 119 (Fig. 3). The shaft 119 extends toward the left and is journaled in a bearing of plate 111. The body 168 of the potentiometer P is mounted and keyed on the shaft 119 and hence has always a fixed angular position relative to the shaft. The knob 120 serves for turning the shaft 119 and is firmly attached thereto. A flange member 83 is fastened and keyed to shaft 119 and carries an insulating plate 114 with two spring clips 84 and 85. The insulating bottom plate 110 of the drum D has two corresponding openings 86 and 87 (Figs. 6 and 7), and the metallic drum cylinder 113 has two slots for engagement by clips 84 and 85, respectively.

Drum D can be pulled out of engagement with clips 84 and 85 and through the opening of plate 122 for fastening or exchanging a diagram sheet on the drum surface. When inserting the drum, its proper angular position relative to shaft 119 is secured by the clips and the latter serve also to connect the drum cylinder 113 electrically with a terminal 169. A friction device or stop (not shown) may be provided to prevent the drum from rotating unless moved by hand.

Due to the fact that the usually stationary portion of the potentiometer, including the resistor corresponding to item 68 in Fig. 4, is rotatable together with the drum, the drum rotation does not interfere with the recording operation. Consequently, the drum can be placed into any convenient position during a recording procedure without requiring an interruption of the operation.

The foregoing description refers especially to recorders in which one coordinate is time and therefore the axial translation of the stylus assembly derived from the drive or transmission mechanism for rotating the stylus. For a recorder in which the axial movement represents a magnitude not proportional to time (X-Y-recorder), the gear 57 (Fig. 3) or 157 (Fig. 6) is not connected to the motor drive of shaft 49 (Fig. 2), but is geared to a separate drive which is controlled in dependence upon the component magnitude represented by the axial coordinate of the recording. That is, the rotary drive of the stylus and the relative axial translating motion between stylus and drum can be derived from any two suitable sources of motion under control by different and not necessarily interdependent quantities. For many purposes it is desirable to have the stylus not rotate continuously and to keep the recorder at rest for a period of time after each rotation of the stylus. This can be obtained in

either above-described embodiment by employing a start-stop drive instead of the continuously running and directly coupled motor 55 (see Fig. 1).

Another embodiment of a recorder which lends itself readily to either time proportional or X-Y recording, is represented in Fig. 8, mainly by an illustration of those of its parts that are different from the recorders described previously. The last two digits of the reference numerals used in Fig. 8 are identical with the numerals of Figs. 1 to 3 wherever similar elements are concerned.

According to Fig. 8, the flange member 229 and gear 230 of the annular member, carrying the bracket 228 and the spring biased holder 226 of the stylus 225, are rotatably held at a fixed distance from the plates 222 and 213 of the stationary supporting and base structure of the apparatus, the flange 229 being guided by rollers 20 such as the one denoted by 231. The recorder drum is composed of a drum cylinder 218 and a top plate 217 and carries a stud 219 with a knob 220. The drum is supported by a composite carrier structure formed of two piston-shaped disk members 88 and 89 which are rigidly interconnected by two rods 90 and 91. The rods are slidably guided in two tubes 82 and 83 firmly mounted on the base plate 213. A centrally located feed screw 84 is journalled in plate 213 and engages a nut 85 rigidly attached to a neck portion 96 of disk member 89. A gear 87 on feed screw 84 serves to revolve it and is geared either to the drive or transmission means (not shown in Fig. 8) for rotating the stylus when time-proportional operation is intended or to a separate drive under a not necessarily time proportional control when X-Y recording is intended. The drum cylinder is frictionally held on the flange portions of disk members 88 and 89 so that it cannot rotate relative thereto unless the knob 220 is turned manually. Knob 220 serves also to pull the drum out of its seat for loading it with recording paper. Referring to a time proportional operation, the drum is located as shown in Fig. 8 when starting the operation. As the stylus is rotated and intermittently energized in the manner explained above, the feed screw 84 lifts the nut 85 and the entire carrier structure and thereby causes the drum to protrude more and more from the plate 222, thus exposing the diagram as it is being written by the rotating stylus. It will be understood that the drum carrier can be connected with the normally stationary portion of a potentiometer as explained with reference to Fig. 6 if it is desired to permit rotating the drum by hand without interruption of the diagram or recording operation. An apparatus of this type is also applicable in cases where the rotation of the stylus is not continuous but occurs intermittently in regular or irregular intervals as obtainable by means of start-stop drives, for instance.

While the above-described embodiments involve the use of electro-responsive recording paper in conjunction with an electrode-type stylus, my invention is not limited to this particular type apparatus. It is further not obligatory, within the principles of my invention, to have the stylus rotate cyclically or periodically or always through the complete peripheral range of available angular motion. This will be understood from the embodiment of a continuously writing recorder diagrammatically illustrated in Fig. 9.

The apparatus shown in Fig. 9 is in many respects similar to that of Figs. 1 to 3 or 6. As a matter of fact, the recorder may be identical with that of Figs. 1 to 3 as regards all parts denoted in Fig. 9 by the same reference characters as those used in Figs. 1 to 3. The stylus 325, however, is an ink pen or the like device which writes a line 380 on the recording surface of drum D in accordance with any relative motion between the drum and the member M carrying the stylus. Obviously, a recorder of this kind does not operate with a control circuit as typified by Fig. 4 but instead requires the rotary stylus motion to be controlled in dependence upon a control magnitude. Assuming, for instance, that the relative axial translation between stylus and drum is time proportional, the rotary motion of the stylus is to be controlled in accordance with the variations of the quantity to be recorded versus time. To this end, the motor 355, used for rotating the stylus carrier M through gears 53 and 52, shaft 49 and gears 50 and 51, is of the reversible type. Its two reversing circuits are connected to a current source 37 through a movable contact 378 and the stationary contacts 375 and 376 of a polarized relay whose control coil 377 is connected to a measuring circuit which includes the potentiometer P. The slider 86 of the potentiometer resistor 368 is connected by shaft 67 and gears 67, 56 with the transmission shaft 49 of the stylus drive so that it rotates together with the stylus with a transmission ratio of 1:1. Hence, each rotary movement of the stylus causes a simultaneous adjustment of the slider contact along resistor 368.

The terminal points 375 and 376 of resistor 368 are connected with fixed and variable impedance devices 98 and 99, respectively. The impedance device 99 represents a measuring gauge which changes its impedance value in response to the phenomenon or quantity to be recorded. Resistor 368 and impedance devices 98 and 99 form a Wheatstone bridge circuit whose zero branch or output diagonal includes the relay coil 377, while the input or feed diagonal is connected to a current source 100 of constant voltage.

As long as the two impedance values of devices 98 and 99 are equal or at a given ratio, the bridge circuit is balanced when the slider 86 engages a given balance point, for instance, the midpoint, of resistor 368. In this slider position, no voltage drop occurs across the relay coil 377 so that contact 378 assumes an inoperative mid-position. As a result, the motor 355 is deenergized and at rest, and the stylus performs no rotation. When the impedance of gauge 99 departs from the balance value, a voltage drop appears across relay coil 377 in a direction depending upon that of the impedance departure and causes contact 378 to engage contact 375 or 376. This has the effect of energizing the motor 355 so that stylus 325 and slider 86 are rotated in the direction in which the slider reduces the unbalance of the bridge circuit until balance is reestablished and the motor stopped. As a result, the stylus and slider perform a follow-up motion whenever an impedance change in gauge 99 occurs and tend to maintain an angular position which, at any time, is indicative of the quantity to be measured. Therefore, the solid-line curve 380 recorded by the apparatus represents the measured quantity versus time. The axial translating means are not shown in Fig. 9, but may be identical with those shown in Fig. 1, 6 or 8. Axial displacement may be achieved by a timing motor or, in the case of an X-Y recorder,

by any reversible motor responsive to the quantity to be recorded along the abscissa.

Recording apparatus according to the invention are, of course, also applicable for recording non-electric variations and, for such uses, need not necessarily be provided with the above-described driven potentiometers. Referring, for instance, to Fig. 9, the rotary stylus assembly, instead of being driven by a motor, can be linked directly to a measuring element producing a rotary motion. For example, in a strain-stress recorder, the stylus carrier can be driven by a mechanical gauge whose angle of rotation is proportional to a deformation or other stress, to be measured, while the axial translating device may be coupled with the strain-measuring device or transmission of the testing machine. Such a recorder need not be provided with electric control means.

While the above-described embodiments of the invention contain an electric potentiometric device for controlling the recording operation, it will be understood that the above-elucidated principles and structural features of the invention are also applicable to recording apparatus having other types of control devices associated therewith. This will be more fully understood from the following example of a recorder having a mechanical "potentiometric" or tensiometric relay control device.

Referring to Fig. 10, a drum and stylus mechanism with rotatory and translating drive means designed in accordance with the above-described embodiments is combined with a special type measuring relay SR whose movable contact is biased by an oscillating spring mechanism which changes the biasing force or torque of the spring through a given range of variation in much the same way as the effective potentiometric voltage is changed and applied to a relay in electric potentiometric control devices of the type previously described. Since the operating principle of such oscillatory spring relays is known as such, the following description is limited to its essentials and its adaptation to, and combination with, a rotating stylus recorder in accordance with the invention.

As in the embodiments of Figs. 1 through 9, the apparatus represented by Fig. 10 has a drum D provided with a knob 20 and surrounded by an annular carrier M for the stylus 25. Member M is rotated by means of gear 50, shaft 49, bevel gears 57 and 53 by a motor 55, while performing an axial translating motion relative to drum D which is produced by means (not shown in Fig. 10) similar to those of Figs. 1 through 6, for instance. Gear 456 and 457 form a transmission between the stylus means and the relay SR and drive a cam O in synchronism with the stylus rotation.

The relay SR is of the moving coil galvanometer type. It has a permanent field magnet E and a moving coil 477. The coil is mounted on a shaft F which carries a contact cooperating with stationary contacts 475 and 476 for controlling a discharge circuit C of the type described above in conjunction with Fig. 4. The coil 477 is electrically connected to a measuring or control gauge G, through an amplifier A, if desired. The biasing torque, to be overcome by that of the energized coil 477, is provided by a spiral spring 474. The inner end of spring 474 engages shaft F and the outer end is attached to a stud G mounted on a gear H which is freely rotatable about shaft F. Magnet E and contacts 475 and 476 are mounted on the stationary structure of

the recording apparatus and thus remain stationary during the operation of the relay. Hence, the biasing torque imposed on coil 477 by spring 474 depends on the angular position of stud G relative to the stationary parts and can be varied continuously by rotating the gear H. Such rotation is effected by means of a gear I whose shaft carries a follower arm K with a stop L held against cam O by a spring N.

When the stylus drive rotates in the direction of the arrow Q, cam O completes a full rotation for each rotation of the stylus and moves the follower K from a lowermost to an uppermost position. Upon completion of each rotary cycle, the follower drops back to the lowermost position. As a result, the spring 474 has lowest tension at the start and increases it gradually to a maximum at the end of each cycle. At the time point within each cycle when the coil torque caused by the measuring quantity effective in gauge G exceeds the biasing torque of the spring 474, the movable contact of relay SR switches from contact 475 to contact 476 and causes the stylus to write a recording mark. This takes place at an earlier or later moment within each cycle depending upon the magnitude of the measuring quantity. The angular position of stud G, gear I, arm K or stylus 25 at the occurrence of the switching over is indicative of this magnitude. Consequently, the position of the recording mark produced by the stylus, relative to the recording surface or sheet, is also representative of the magnitude to be measured.

The embodiments of recording apparatus shown in Figs. 11 and 12 are related to that of Figs. 6 and 7 in that they permit the attendant or observer to rotate the recorder drum in order to place the recorded diagram into a convenient position without interruption of the recording operation. While in the embodiment of Figs. 6 and 7 this is achieved by a rotatable mounting of both the resistor and the slider of the potentiometric control device, it is within the objects of my invention to accomplish similar results with apparatus in which one of the relatively movable parts of the control device is stationarily mounted. To this end, I provide the recorder with a gear type transmission whose two input shafts or gears are connected with the recorder drum and stylus respectively and whose output shaft or gear drives the control device at a given ratio to the differential relative motion between drum and stylus with respect to the peripheral direction of the drum. Both embodiments of Figs. 11 and 12 are designed in this manner.

While the showing in Figs. 11 and 12 is schematic, it will be understood that the base structure B, the drum with knob 20, the rotary member M carrying the stylus 25, shaft 49, gears 50, 52, 53, and motor 55 are similar to the correspondingly designated parts of the recorder shown in Figs. 1 through 5. As a matter of fact, this portion of the apparatus, as well as the axial translating means of the stylus assembly (not shown in Figs. 11 and 12) are preferably of substantially the same design as the corresponding portion more accurately and in detail illustrated in Figs. 1 to 5.

Referring now to Fig. 11 only, the base portion of a resistance potentiometer P, including the potentiometer resistor 568 is firmly and immovably secured to the base structure B of the apparatus, while the appertaining rotary slide contact 566 is driven by a differential gear of the planetary type to be described presently.

The shaft 49 for imparting rotary motion to the stylus assembly carries a gear 557 which is keyed to the shaft or otherwise prevented from rotating relative thereto. Gear 557 meshes with an idler gear T which is firmly connected with another idler gear U and freely rotatable about the apertaining common shaft. Gear U, in turn, engages a gear V mounted on the shaft of slider 566. The common shaft of idler gears T and U is attached to a sleeve X which carries a gear Y and is freely rotatable about shaft 49. Gear Y meshes with a gear Z firmly secured to the shaft 519 of drum D and knob 20. The transmission ratio of each pair of gears 557 and T, U and V is 1:1. Consequently, as long as the drum D remains stationary, the revolution of shaft 49 is transmitted by gear 557 through gears T, U and V to the slider 566 so that the latter rotates at the speed of shaft. The transmission ratio of parts M and 50 is 3:1. Therefore, the potentiometer 20 is actuated through three complete control cycles for each full rotation of the stylus. That is, this particular recorder operates as a triple recorder for producing three individual diagrams spaced peripherally as the recording surface of the drum or sheet in accordance with the principles of the multiple recorders disclosed in the copending application Serial No. 470,088 of George Kleinath, filed December 24, 1942. The selective contact apparatus required for such recorders may be 30 actuated by shaft 519 (not illustrated).

When knob 20 is turned in order to revolve the drum, gear Z rotates gear X and, hence, the shaft of the idler gears T and U about the axis of shaft 49. As a result, a cumulative or subtractive motion is superimposed on the rotation of gear V depending upon the direction of rotation of the drum shaft so that the motion of slider 566 relative to resistor 568 maintains its speed and angular relation to the relative rotary motion between stylus and drum. As a rule, however, I prefer preventing the drum from rotating in the direction of stylus rotation. A ratchet gear (not shown) may be provided to secure this way of operation, and it is in most cases necessary to insert an idler gear between gears Z and Y to obtain the proper relation of the directions of the angular potentiometer rotation and the superimposed rotation due to the drum motion. It will be apparent from the foregoing that the ratio of gears Z and Y should be chosen so that a rotation of the drum against the direction of stylus rotation by the width of one recorded diagram should advance the potentiometer slider by one revolution.

The recording apparatus according to Fig. 12 is provided with a control device of the relay type shown in Fig. 10. The base of the oscillating spring relay SR is rigidly mounted on the stationary structure B of the apparatus, and the cam member O' for oscillating the adjusting member K of the biasing spring is driven by a planetary gear transmission similar, except for its gear ratios, to the above-described gearing of Fig. 11. The cam member O' of the spring relay SR has five lobes so that one-fifth of one revolution (72°) suffices to change the adjustment of the relay through one full cycle. The recorder is intended for producing a single diagram per chart (as is the case in the recorders shown in Figs. 1 through 10). Consequently, the differential gear transmission is so chosen that one complete rotation of the drum shaft 519 against the direction of rotation of the stylus assembly advances the cam O' of the oscillating spring relay

SR by one-fifth of one revolution (72°). In accordance therewith, the gear ratios are as follows:

- 5 Ratio of gears M and 50: 3 to 1
Ratio of gears Z' and Y': 1 to 5
Ratio of gears 557 and T': 1 to 3
Ratio of gears U' and V': 1 to 5

The shaft of the planetary idler gears T' and U' is mounted on gear Y'. As long as the drum D remains at rest, the rotary motion of the stylus assembly is transmitted to cam O' at a ratio of 1 to 5. That is, the relay is adjusted once through a full cycle of 72° for each full rotation of the assembly. When the drum D is rotated by actuating knob 20 and shaft 519, the cam O' is additionally advanced at the correct rate so as to maintain the original speed or angular relation to the relative rotation between stylus and drum.

While I have shown and described in detail a number of different recording apparatus in which a stylus rotates about a recording surface relative to which it is also displaceable at an angle to its rotation, it will be understood by those skilled in the art, on the basis of the foregoing disclosure, that this and the other above-described principles of my invention can also be embodied in apparatus of structurally different design or appearance without departing from the essential features and the spirit of my invention as set forth in the following claims:

What I claim is:

1. A recording apparatus comprising a drum for accommodating a recording sheet, an annular member surrounding said drum and being rotatable relative thereto, stylus means mounted on said member for producing a record on said sheet, a non-rotary support carrying said member and being movable axially along said drum, drive means for rotating said member, and a drive mechanism engaging said support for moving it along said drum.

2. A recording apparatus comprising a base structure, a recorder drum mounted on said structure, a carrier member coaxially rotatable relative to said drum, stylus means mounted on said member for producing a record along the peripheral surface of said drum, means for rotatably supporting said member, a threaded shaft extending along said drum for engaging said supporting means in order to move it axially with respect to said drum, another shaft extending along said drum and having transmission means for engaging said member in order to impart rotation thereto, and drive means mounted on said base structure for revolving said two shafts.

3. A recording apparatus comprising a base structure, a recorder drum mounted on said structure, a carrier member coaxially rotatable relative to said drum, stylus means mounted on said member so as to be rotatable together therewith for producing a record along the peripheral surface of said drum, means for rotatably supporting said member, a threaded shaft extending along said drum for engaging said supporting means in order to move it axially with respect to said drum, another shaft extending along said drum and having gear means for engaging said member in order to impart rotation thereto, drive means mechanically connected to one of said shafts for revolving it in accordance with a control magnitude, and drive means mechanically connected to said other shaft for revolving

it in accordance with another control magnitude.

4. A recording apparatus comprising a base structure, a recorder drum mounted on said structure, a carrier member coaxially rotatable relative to said drum, stylus means mounted on said member so as to be rotatable together therewith for producing a record along the peripheral surface of said drum, means for rotatably supporting said member, a threaded shaft extending along said drum for engaging said supporting means in order to move it axially with respect to said drum, another shaft extending along said drum and having gear means for engaging said member in order to impart rotation thereto, drive means geared to said two shafts for revolving them in a given relation to each other, and control means for rendering said stylus means operative to produce said record at points of its travel relative to said drum in accordance with a control magnitude to be recorded.

5. A recording apparatus comprising a base structure, a recorder drum mounted on said structure, a carrier member coaxially rotatable relative to said drum, stylus means mounted on said member so as to be rotatable together therewith for producing a record along the peripheral surface of said drum, means for rotatably supporting said member, a threaded shaft extending along said drum for engaging said supporting means in order to move it axially with respect to said drum, another shaft extending along said drum and having gear means for engaging said member in order to impart rotation thereto, drive means mounted on said base structure for revolving said two shafts, and control means disposed for actuating said stylus means in accordance with a control magnitude and comprising an impedance device mounted on said base structure and geared to one of said shafts so as to vary its impedance in a given relation to the revolution of said shaft.

6. A recording apparatus comprising a drum for accommodating a recording sheet, stylus means arranged for marking the sheet and being rotatable about the axis of said drum, said drum and stylus means being axially displaceable relatively to each other, drive means for imparting rotation to said stylus means, a relay mechanism having electric contact means for controlling the marking operation of said stylus means in accordance with a quantity to be recorded and being provided with contact biasing means having a movable member for varying the biasing effect of said biasing means through a given range of variation, said member being connected with said drive means so as to move in a given relation to the rotation of said stylus means, and drive means for axially displacing said stylus means and sheet relative to each other.

7. A recording apparatus comprising a rotatable drum for accommodating a recording sheet, stylus means disposed for marking said sheet and being rotatable about said drum, said drum and stylus means being axially displaceable relative to each other so that said stylus means is operable when said drum is non-rotating, a device disposed for controlling the marking operation of said stylus means and having a stationary part and a member rotatable relative to said part for adjusting the control effect of said device, and a planetary gear transmission having two input gears connected with said drum and stylus means, respectively, and an output gear connected with said member for rotating it in a given ratio to

resultant relative rotation between said drum and said stylus means.

8. A recording apparatus comprising a rotatable drum for accommodating a recording sheet, stylus means disposed for producing a record on said sheet and being rotatable about said drum, said drum and stylus means being axially displaceable relative to each other so that said stylus means is operable when said drum is non-rotating, a potentiometric measuring device disposed for controlling the writing operation of said stylus means in accordance with a quantity to be recorded and having a stationary member and a rotary member cooperative for varying the potentiometric control effect of said device, and a differential transmission connecting said drum and said stylus means with said rotary member so as to rotate the latter in a given ratio to resultant relative rotation between said drum and said stylus means.

9. A recording apparatus comprising a rotatable drum for accommodating a recording sheet, stylus means disposed for producing a record on said sheet and being rotatable about said drum, said drum and stylus means being axially displaceable relative to each other so that said stylus means is operable when said drum is non-rotating, a relay mechanism having electric contacts for controlling the writing operation of said stylus means in accordance with a quantity to be recorded and being provided with contact biasing means having a stationary member and a rotary member cooperative for varying the biasing effect of said biasing means, and a differential transmission connecting said drum and said stylus means with said rotary member so as to rotate the latter in a given ratio to resultant relative rotation between said drum and said stylus means.

10. A recording apparatus comprising a normally non-rotating but manually rotatable drum for accommodating a recording sheet, stylus means disposed for producing a record on said sheet and being rotatable about said drum, said drum and stylus means being axially displaceable relative to each other so that said stylus means is operable when said drum is non-rotating, an oscillating spring relay having electric contact means for controlling the writing operation of said stylus means in accordance with a quantity to be recorded and being provided with a contact biasing spring and a movable member for varying the biasing effect of said spring through a given range of variation, and a differential gear transmission connecting said drum and said stylus means with said member so as to move said member in a given ratio to resultant relative rotation between said drum and said stylus.

11. A recording apparatus comprising a drum for accommodating a recording sheet, a revolvable annular member surrounding said drum and having an annular gear coaxial to said drum, stylus means mounted on said member for producing a record on said sheet, drive means having a gear in engagement with said annular gear for revolving said annular member, and drive means for producing relative motion between said drum and said member in the axial direction of said drum.

12. A recording apparatus comprising a drum for accommodating a recording sheet, an annular member surrounding said drum, stylus means mounted in said member for producing a record on said sheet, a non-rotary support having guide

means in engagement with said member for permitting it to revolve relative to said support about said drum, drive means comprising a feed screw extending in parallel to the axis of said drum and member for imparting thereto relative motion in the axial direction of said drum, and drive means engaging said member for imparting revolving motion thereto.

13. A recording apparatus comprising a stationary structure, a normally non-rotating but manually rotatable drum for accommodating a record sheet, said drum being secured to said structure so as to be removable therefrom, an annular member surrounding said drum, a non-rotary support secured to said structure and having bearing means in engagement with said member for permitting it to revolve relative to said support about said drum, a stylus mounted on said member for producing a record on the sheet, drive means comprising a feed screw extending parallel to the axis of said drum and member for imparting thereto relative motion in the axial direction of said drum, and drive means engaging said member for imparting revolving motion thereto.

14. A recording apparatus comprising a drum for accommodating a record sheet, an annular member surrounding said drum, a stylus mounted on said member for producing a record on the sheet and being movable relative to said member toward and away from said drum, a non-rotary support having means for engaging said member so as to permit it to revolve coaxially about said drum and being axially displaceable along said drum, drive means having a feed screw extending in parallel to the axis of said drum, coupling means disposed on said support for engaging said feed screw so that said support is displaced by said drive means when said screw and coupling means are operative, control means on said support for disengaging said coupling means from said screw to permit displacing said support independently of said drive means, and means on said support for holding said stylus away from said drum when said coupling means is disengaged.

15. A recording apparatus comprising a normally non-rotating but manually rotatable drum for accommodating a recording sheet, stylus means disposed for producing a record on said sheet and being rotatable and axially displaceable relative to said drum so as to be operable when said drum is non-rotating, drive means for imparting rotation to said stylus means, drive means for axially displacing said stylus means relative to said drum, electric means for transmitting control impulses on said stylus means so as to cause it to produce recording marks on said sheet indicative of a phenomenon to be recorded, an oscillating spring relay forming part of said electric means and having a base structure, contact means on said structure for controlling said impulses and being provided with a contact biasing spring, and a member movable relative to said structure for varying the biasing effect of said spring through a given range of variation, and gear means connecting said relay with said drum and said stylus means for producing relative motion between said structure and member in a given ratio to resultant relative rotation between said drum and said stylus.

16. A recording apparatus comprising a rotatable drum for accommodating a recording sheet, stylus means disposed for marking the sheet and being rotatable about said drum, said drum and

stylus means being axially displaceable relative to each other so that said stylus means is operable when said drum is non-rotating, a device disposed for controlling the marking operation of said stylus means and having a stationary part and a member movable relative to said part for causing said stylus means to mark the sheet in a position relative to said drum depending upon a singular position of said member relative to said part, and a differential transmission having two input elements connected with said drum and said stylus means respectively, and having an output element connected with said member for moving said member in a given relation to resultant relative rotation between said drum and said stylus means.

17. A recording apparatus comprising a cylindric electrode for accommodating a record sheet, an annular member coaxial with and rotatable about said drum, a stylus electrode mounted on said member for marking the sheet when electrically energized, means for displacing said member in the axial direction relative to the sheet, said annular member having a concentric annular gear, a shaft extending along and in parallel to said cylindric electrode and having a gear meshing with said first gear for rotating said member, a drive connected with said shaft and said displacing means for operating said shaft and said displacing means simultaneously in a given ratio to each other, an electric contact device connected with said drum and said stylus electrode for controlling the marking operation of said stylus electrode, and condition-responsive control means disposed for controlling said contact device and including a member rotatable over a given range in order to cause said contact device to energize said stylus electrode when said latter member passes through a position indicative of a condition to be recorded, and gear means connecting said latter member with said shaft so that said latter member is driven simultaneously with and in a given relation to the rotation of said shaft.

18. A recording apparatus comprising a cylindric electrode for accommodating a record sheet, an annular member coaxial with and rotatable about said drum, a stylus electrode mounted on said member for marking the sheet when electrically energized, a non-rotary structure having bearing means in engagement with said annular member, said annular member having a concentric annular gear, a shaft extending along and in parallel to said cylindric electrode and having a gear meshing with said first gear for rotating said member, a feed screw extending in parallel to said cylindric electrode and engaging said structure for displacing it along said cylindric electrode, gear means coupling said shaft with said feed screw, a drive motor for causing said gear means to revolve said shaft and said screw in a given ratio to each other, an electric contact device connected with said drum and said stylus electrode for controlling the marking operation of said stylus electrode, and condition-responsive control means disposed for controlling said contact device and including a member rotatable over a given range in order to cause said contact device to energize said stylus electrode when said latter member passes through a position indicative of a condition to be recorded, said latter member being geared to said gear means so as to rotate in a given ratio to the revolution of said shaft and said feed screw.
